CLAIM

The ornamental design for a microwell plate assembly, as shown and described.

DESCRIPTION

FIG. 1 is a top perspective view of a first embodiment of a microwell plate assembly.

FIG. 2 is a top view of the microwell plate assembly.

FIG. 3 is a front view of the microwell plate assembly.

FIG. 4 is a back view of the microwell plate assembly.

FIG. 5 is a bottom view of the microwell plate assembly.

FIG. 6 is a side view of the microwell plate assembly.

FIG. 7 is another side view of the microwell plate assembly.

FIG. 8 is an exploded and partially rotated perspective view of the microwell plate assembly.

FIG. 9 is a top perspective view of a second embodiment of a microwell plate assembly.

FIG. 10 is a top view of the microwell plate assembly of FIG. 9.

FIG. 11 is a front view of the microwell plate assembly of FIG. 9.

FIG. 12 is a back view of the microwell plate assembly of FIG. 9.

FIG. 13 is a bottom view of the microwell plate assembly of FIG. 9.

FIG. 14 is a side view of the microwell plate assembly of FIG. 9.

FIG. 15 is another side view of the microwell plate assembly of FIG. 9; and,

FIG. 16 is an exploded and partially rotated perspective view of the microwell plate assembly of FIG. 9.

The broken lines in the figures depict portions of the microwell plate assembly that form no part of the claimed design.
